The ornamental design for a spare tire camera and light system, as shown and described.

DESCRIPTION

FIG. 1 is a front view of a spare tire camera and light system, shown in condition of use with a vehicle disclosed in broken lines to illustrate an environment;

FIG. 2 is a perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the spare tire camera and light system in which the design is embodied that form no part of the claimed design. Additionally, the broken lines showing a vehicle in FIG. 1 represent environmental structure and form no part of the claimed design.
